UNITED STATES PATENT OFFICE

MARK H. DAMERELL, OF WORCESTER, MASSACHUSETTS

SOW-BLOCK HOLDER FOR HAMMERS

Application filed May 11, 1928. Serial No. 276,967.

This invention relates to sow block holders for hammers.

In forging hammers, it is the usual practice to heat the dies carried by the sow blocks, which necessarily imparts heat to the sow blocks. This causes expansion of the sow block while the base to which the sow block is rigidly attached, is not permitted to expand as it is not heated. Consequently, enormous strains are produced and it frequently happens that the bases of the large forging hammers are cracked through from the top to the bottom, thus rendering the entire base unserviceable for any further use.

When it is considered that these bases are of expensive and ponderous construction, and require elaborate supporting foundations, it is apparent that the expense resulting from a cracked base is enormous.

Further than this, in view of the fact that the sow block is relatively small as compared with the base, it is apparent that it heats and cools very quickly, long before any temperature change could possibly affect the base. Thus, there is great danger of cracking, noted above, and also of loosening of the sow block.

Further than this, in certain forms of hammers it is also the practice to carry the die directly upon the base and to secure the die to the base. Under these conditions, the same defects appear due to expansion of the die with consequent danger of cracking the base.

This invention is designed to overcome the defects noted above, and objects of such invention are to provide a novel means of holding the sow block or equivalent member, so that there is no danger of cracking the base, although the sow block may expand when heated.

Further objects are to provide a novel means of holding the sow block which will not loosen when the sow block cools, but which will take up the expansion or contraction while maintaining a rigid and secure connection between the sow block and the base.

Further objects are to provide a novel construction having the characteristics enumerated above, which is easy to assemble and which cannot be dislodged.

An embodiment of the invention is shown in the accompanying drawings in which:

Figure 1 is a side elevation of the bottom portion of a forging hammer;

Figure 2 is a fragmentary plan view of the structure shown in Figure 1.

In the drawings, one form of sow block has been shown, but it is, of course, to be understood that any form of sow block is intended, and also that the drawing illustrates the principle to be employed where the die is carried directly by the base, as previously described, or, in fact, where any relatively massive member carries a relatively small member in the hammer art.

Referring to the drawings, it will be seen that the main base of the forging hammer is indicated by the reference character 1. From this base, a pair of standards 2 rise to the cylinder of the hammer. The base is mounted in any suitable manner, as shown for example in Figure 1.

The upper portion of the base is provided with a transverse cut-out or grooved part which receives the sow block 3. This sow block is provided with an outwardly bulged portion 4 which slants towards opposite sides and which also slants outwardly towards the bottom of the sow block. It fits in a correspondingly shaped dovetailed or slanting portion of the main slot for the reception of the sow block. This construction prevents lateral shifting of the sow block.

The die 5 is keyed by means of the dovetail construction illustrated in Figure 1 to the sow block in the usual manner.

The other face of the sow block is smooth and is tapered as indicated by the reference character 6 in Figure 1. It fits within the overhanging or dovetailed side of the groove formed in the base and is spaced therefrom. This side of the groove is indicated by the reference character 8.

A corrugated steel shim 9 is positioned immediately adjacent the face 6 of the sow block and has its ends 9' turned over the ends of the sow block to prevent displacement. It does not fill the entire groove, and the rest of the groove is filled by means of a hardened straight shim 10 having an outwardly turned

end 11 to hold it in place, and a tapered key 12 having an outwardly turned locating end 13.

In assembling the apparatus, the sow block 5 is positioned, as shown in Figure 2 with the corrugated shim 9. Thereafter, the shim 10 is slipped into place and subsequently the tapered key 12 is driven into place. This tapered key bears against the hardened shim 10 and the hardened shim prevents cutting of either the key or the corrugated shim.

Further than this, when the tapered key is driven into place, it slightly compresses the corrugated shim and thus produces the requisite pressure against the side of the sow block and thus locks the sow block in place.

It is apparent that when the die is heated prior to the forging operation, that heat is transmitted to the sow block. This causes 20 expansion of the sow block and when it is considered that the base does not expand, it will be immediately appreciated that the corrugated steel shim 9 takes up this expansion and maintains the pressure substantially uniform against the sow block without allowing any dangerous increase in pressure. There is, consequently, no danger whatsoever of cracking the base due to expansion of the sow block.

30 Further than this, cooling of the sow block does not loosen it as the corrugated shim 9 takes up any change in size of the sow block with reference to the base.

In view of the fact that the devices 35 described, namely, the corrugated shim 9, the hardened shim 10, and the key 12, are set at slightly different angles with respect to the vertical, as shown in Figure 1, it is apparent that none of them can pull upwardly out of 40 place. In fact, each one is locked by a dovetail action, as is apparent from this figure.

It will be seen, therefore, that a very simple and secure construction has been provided by this invention which will retain the 45 sow block in place, irrespective of expansion or contraction, and which will not allow cracking of the base, but which takes up any variation in relative size of the sow block and base.

50 It is intended that the term "sow block" be given its usual meaning and also such meaning as will include any similar device. For instance, the expressions "anvil cap", "chair", "die chair", "shoe", "die shoe", and "sow 55 block", are all used in the same sense, and it is therefore, intended that the expression "sow block" be interpreted to cover all of these expressions or any similar expression. Further, as previously mentioned, it is sometimes the practice to key the die proper directly to the base without the use of an intermediate sow block proper. Therefore, to avoid needless repetitions of claims and expressions 60 therein, it is intended that the expression 65

"sow block" be interpreted to include a "die" also.

Although the invention has been described in considerable detail, such description is intended as illustrative rather than limiting 70 as the invention may be variously embodied and as the scope of such invention is to be determined as claimed.

I claim:

1. In a hammer having a base provided 75 with a slot having overhanging slanting side walls, a sow block having slanting sides, a corrugated shim and a hardened straight shim interposed between a side of the sow block and a side of the slot, and a wedge 80 driven between the hardened straight shim and the adjacent side of the slot.

2. In a hammer having a base provided with a slot having overhanging slanting side walls, a sow block having slanting sides, a 85 corrugated shim and a hardened straight shim interposed between a side of the sow block and a side of the slot, and a wedge driven between the hardened straight shim and the adjacent side of the slot, said shims and wedge 90 being arranged at different angles to the vertical.

In testimony that I claim the foregoing I have hereunto set my hand at Worcester, in the county of Worcester and State of Massa- 95 chusetts.

MARK H. DAMERELL.
